Primary Examiner — Susan Bennett Hattan*Assistant Examiner* — Janice Hallmark(74) *Attorney, Agent, or Firm* — Banner & Witcoff, Ltd(57) **CLAIM**

The ornamental design for a handset cradle, as shown and described.

DESCRIPTION

FIG. 1 is a perspective view of a handset cradle showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The contrast in shading shown in FIGS. 1, 2, and 4-7 represents a change in appearance only. The broken lines showing of the environment and the remainder of the handset cradle in FIGS. 1-7 are for environmental purposes only and form no part of the claimed design.
